UNITED STATES PATENT OFFICE.

GEORGE H. HARPER, OF COLUMBIA CITY, INDIANA.

STORM-TOP FOR BUGGIES.

1,099,798.

Specification of Letters Patent.

Patented June 9, 1914.

Application filed July 27, 1911. Serial No. 640,777.

To all whom it may concern:

Be it known that I, GEORGE H. HARPER, a citizen of the United States, residing at Columbia City, in the county of Whitley and 5 State of Indiana, have invented certain new and useful Improvements in Storm-Tops for Buggies; and I do declare the following to be a full, clear, and exact description of the invention, such as will enable others skilled 10 in the art to which it appertains to make and use the same.

This invention relates to carriages and wagons, and more especially to the tops thereof; and the object of the same is to produce an improved storm top or body which can be attached to or which may form part of a buggy body, the same having a door opening closed by a sliding door which itself can be instantly removed at will. These objects are accomplished by certain specific features of improvement as set forth in the following specification and claim and shown in the drawings wherein—

Figure 1 is a side elevation of this improved storm top; Fig. 2 is a section on the line 2—2 of Fig. 1; Fig. 3 is a horizontal section on the line 3—3 of Fig. 1; Fig. 4 is a front elevation; Figs. 5 and 6 are enlarged vertical sections through the door and the 25 top bow, and an elevation of the intermediate standard or upright.

In the drawings the numeral 1 designates the body or box which is constructed much as usual excepting that its sides 2 are slightly 30 curved outward along their upper edges so that the body is wider at its center than it is at its front or rear; and the numeral 3 designates the seat fixedly or removably mounted upon said body at about the center 40 of its length.

My improved storm top, which may be either fixedly or removably attached to the seat, comprises two principal parts whereof only the doors and windows need be movable 45 and the remaining portions are immovable with respect to the seat and the body.

The superstructure of this improved top may be roughly described as embracing uprights 5, 6 and 7, a top 8, a back 9, and side 50 panels 10, in addition to which a front panel or curtain may be used if desired. Said panels and the back may have glass or mica windows inserted if desired, and the specific details of this superstructure are unimportant save that there will be door-openings 55 at each side of the storm top just forward

of the seat. So also the specific details of the door structure are not essential excepting of course that the doors should be slightly wider than the door-openings so as to close 60 over the same, but the gist of my invention lies in the manner in which they are slidably mounted upon guides which conform with the general shape of the sides 2 of the body 1 and are removable at will. 65

The upper portion of each door is panelled as at 11 to conform to the paneling of the side 10, so that when the door is moved back opposite the side the glass panes will register and the occupant can look out; but 70 the lower portion 12 of the door is by preference solid, and inclined inward to conform with the inclination of the seat-end, than which it is by preference a little higher or wider so that its lower edge when it is in 75 place will engage a track or guide 13 mounted beneath the door opening on the outside of the body 1 below the extreme upper edge of the latter, and water running down the outside of the door will therefore be shed 80 away from and out of the box. This guide is preferably L-shaped as seen in section in Fig. 2, and open at its rear end for a purpose to appear below.

At the angle between the upper and lower 85 portions 11 and 12 of the door, the latter carries along its inner surface a track 14 having an upturned flange 15; and the upright 6 just in rear of the door opening carries a bracket 16 having a downturned lip 90 17 which engages behind said flange. Along the top of the door is secured the upper track 18 having at its inner edge a downturned flange 19, and the same upright has a bracket 20 engaging beneath said track 95 and under its flange in a manner well illustrated. In order to effect this engagement at the upper and lower portions of the door, the upright will be notched out as shown at 21 and 22 so that the flanged edges of the 100 tracks can project into the notches. Both tracks 14 and 18 are open at their front ends for a purpose to appear below.

The lower ends of the bows 30 which support the top 8 will be carried over and secured to the outer faces of the uprights so 105 that such ends will stand in a plane above the door, and the lower side edges of the top-leather will carry a valance 31 which will overhang the upper edges of the doors 110 so as to shed onto their outer faces the water running down off the top.

Thus it will be seen that I have produced an improved storm top for buggies which obviously can be made as a permanent part of the body or as an attachment thereto 5 without departing from the spirit of my invention, and whereof also the several panels could be of flexible material or otherwise.

The door slides easily along the guide or track 13 which of course must be long enough 10 to support it even when moved far to the rear, and while the brackets 16 and 20 have been described as only on the intermediate upright 6 they might be duplicated on the front upright 5 if thought desirable. While 15 their principal function is to hold the door upright as it slides along the guide 13, it is possible that the latter might be omitted and the weight of the door carried by its upper track 18. If the door is not desired for 20 use it can be moved off the open rear end of the guide 13 and the open front ends of its own tracks will disengage the brackets on the upright, but ordinarily it will be moved to the rear only far enough to disclose the 25 door opening as seen in dotted lines in Fig. 3 so as to permit ingress to and egress from the body. The curved shape of the body and doors is much more pleasing to the eye than an ordinary rectangular or box-shaped 30 body, is more cheaply constructed and much lighter, and permits the front to be made about nine inches less in width so that the wind resistance is reduced.

The materials and specific structure of 35 parts are not essential to this invention, and

I have purposely avoided amplification of collateral details such as the curtains and windows.

What is claimed as new is:

A storm top for buggy bodies including 40 uprights rising from the wall of the body in spaced relation to provide a door opening, the upper edge of the body at the juncture of one of said uprights therewith being formed with a channel and with a recess 45 opening into said channel, an L-shaped guide secured to the upright within the channel of the body edge, the angle portion of said guide depending within the recess of the body edge, said upright being formed remote 50 from the body with a recess, a bracket plate secured to the upright and particularly closing the mouth of the recess in said portion of the upright, a door, an L-shaped bracket secured to the upper edge of the 55 door and having its angle portion turned downwardly and engaging the bracket plate and operating within the recess in the upper portion of the upright, and a bracket carried by the door and coöperating from beneath 60 with the L-shaped guide secured to the upright at its juncture with the body edge.

In testimony whereof I have hereunto set my hand in presence of two subscribing witnesses.

GEORGE H. HARPER.
